By his Attorney, Maria Louise White,
Executive
Tom Bodge

UNITED STATES PATENT OFFICE.

BRUCE CLARK WHITE, DECEASED, LATE OF NEW YORK, N. Y.; BY MARIE LOUISA WHITE, EXECUTRIX, OF NEW YORK, N. Y.

ROTARY PRINTING PRESS.

Application filed August 28, 1924. Serial No. 734,667.

- This invention relates generally to rotary printing presses of the type in which a rotary sheet carrier is arranged to present individual sheets to the printing rolls. The 5 present invention has more particular reference to the construction and operation of the sheet gripping devices upon a transfer element which receives the sheet from a pile feeder or the like and transfers it to 10 the carrier, the gripping devices forming the subject matter of the present application being shown in part in a previous application for patent filed by Bruce C. White on April 18, 1922; Serial No. 554,886.
- 15 The invention has for an object to provide a novel and improved form of sheet gripper of simple construction arranged to have a more direct gripping action than the grippers now in use.
- 20 A further object of the invention is to provide a gripper having a resilient gripping action whereby the individual grippers of a series operated by a common means may adjust themselves to insure efficient operation of each gripper.

For further comprehension of the invention, and of the objects and advantages thereof, reference will be had to the following description and accompanying drawing, and to the appended claims in which the various novel features of the invention are more particularly set forth.

Fig. 1 of the drawing is a side elevational view showing one of the sections of the sheet transfer drum with my improved sheet gripper applied thereto, the drum shaft and the shaft for operating the gripper being shown in transverse section.

Fig. 2 is a part plan and part horizontal 35 sectional view of the parts shown in Fig. 1.

Fig. 3 is a detail plan view showing the hub portion of the gripper device.

Fig. 4 is a vertical sectional view taken on the line 4—4 of the Fig. 3.

Fig. 5 is a horizontal sectional view taken on the line 5—5 of Fig. 4.

In the drawing the reference numeral 10 indicates one of the disk segments of a segmental drum which receives the sheet from 50 an inclined feed board 11 to transfer the same to the sheet carrier, and 12 the shaft on which said drum is fixed. The manner in which this transfer is effected does not

affect the present invention which concerns itself with the sheet gripping means. It 55 will be understood that there are a series of these segments each with its individual gripper device. Extending parallel to the shaft 12, and freely supported by the various drum segments, is a shaft 14 by which 60 the gripper members are operated, this shaft having fixed on one end thereof an arm 15 on which is a roller 16 engaging a grooved cam 17 whereby the shaft 14 is rocked at appropriate times to operate the 65 grippers.

Each gripper device comprises, briefly, a short arm mounted on the shaft 14 and a gripper finger which is pivotally connected at one end to the said arm and has its 70 other end adapted to bear on the periphery of the drum segment. The arm on the shaft comprises the hub 20, which encircles the shaft 14, and the lug or ear 21 projected from said hub. The gripper finger is in a 75 form of the bar 22 which is pivotally connected to the ear 21 at its inner end and projects in a generally radial direction outwardly in front of the leading edge of the drum segment. This finger has a rear- 80 wardly turned outer end 22' which is adapted to bear on the periphery of the segment 10 to clamp the sheet in place. A pair of short guiding and supporting links 24 are pivotally connected at one end to the 85 finger 22 a short distance from the outer end thereof, the other ends of these links being pivotally connected to the drum seg- 90 ments 10 as at 25.

The hub 20 is mounted on the shaft 14 90 in a manner to impart a resilient pulling or clamping action on the gripper finger as follows: formed in one side of the shaft is a longitudinal groove 27 of triangular cross section whose two walls are vertical to 95 one another. The hub 20 is thickened along one side to form a lateral rib or projection 28 whose face is substantially parallel to one wall of the groove. This rib is formed with two borings 29 which extend inwardly 100 and communicate at their inner ends with the groove 27, these borings being spaced axially of the hub and being generally vertical to the said wall of the groove. Located in these borings are the coiled com- 105 pression springs 30 which bear at their inner

ends against the said wall of the groove. The outer portions of the borings 29 are threaded to receive the screws 31 which bear against the outer ends of the springs 30. 5 As will be apparent when the springs are compressed to normal operative condition between the screws 31 and the wall of the groove 27 they tend to rotate the hub upon the shaft, and to limit this movement an 10 abutment screw 32 is threaded through the hubs at right angles to the screws 31 and between the latter, and bears on the other wall of the groove. This screw is provided with a lock nut 33. 15 In the operation of the gripper, when the shaft 14 is rocked in the manner described in the above mentioned copending application, the motion thereof is transmitted to the hub 20 through the medium of the springs 20 30 which form a resilient operative element interposed between the shaft and the gripper finger. By this means slight variations in the relation of the various grippers to their drum segments is accommodated and all the 25 grippers are caused to function properly. The particular type of gripper finger here shown, with swinging fulcrum mounting between its ends, is advantageous in that the outer end of the gripper in its movement is 30 adapted to release the sheet and clear the path thereof in its transfer to the carrier. Suitable collars, such as those indicated at 35, may be fixed to the shaft 14 to retain the hubs of the grippers against longitudinal movement thereon.

Having thus described the invention what I claim as new and desire to protect by Letters Patent of the United States is as follows:—

40 1. In combination with a rotary sheet transfer element, a gripper bar having at its outer end a gripper member adapted to engage the sheet, a swinging fulcrum mounting between the ends of said bar, a rock arm 45 connected to the inner end of said bar, and a spring carried by said arm and disposed to effect the clamping action of said gripper member.

2. In combination with a rotary sheet 50 transfer element, a gripper bar having at its outer end a gripper member adapted to engage the sheet, a swinging fulcrum mounting between the ends of said bar, a rock arm connected to the inner end of said bar, a spring carried by said arm and disposed to effect the clamping action of said gripper member, and means for varying the tension of said spring.

60 3. In combination with a rotary sheet transfer element, a gripper bar having at its outer end a gripper member adapted to engage the sheet, a swinging fulcrum mounting between the ends of said bar, a rock shaft, an arm loosely mounted on said shaft and connected to the inner end of said bar,

and a spring carried by said arm and engaging said shaft and disposed to effect the clamping action of said gripper member.

4. In combination with a rotary sheet transfer element, a gripper bar having at its outer end a gripper member adapted to engage the sheet, a swinging fulcrum mounting between the ends of said bar, a rock shaft, an arm loosely mounted on said shaft and connected to the inner end of said bar, 75 a spring carried by said arm and engaging said shaft and disposed to effect the clamping action of said gripper member, and means for varying the tension of said spring.

5. In combination with a rotary sheet transfer element, a gripper bar having at its outer end a gripper member adapted to engage the sheet, a swinging fulcrum mounting between the ends of said bar, a rock shaft having a groove formed therein, an arm loosely mounted on said shaft and connected to the inner end of said bar, a spring carried by said arm and engaging a wall of the groove formed in said shaft and disposed to effect the clamping action of said 90 gripper member, and a stop screw threaded in said arm and engaging a wall of the groove formed in said shaft and adapted to limit the thrust of said spring.

6. In combination with a rotary sheet transfer element, a gripper bar having at its outer end a gripper member adapted to engage the sheet, a swinging fulcrum mounting between the ends of said bar, a rock shaft having a groove formed therein, an arm 100 loosely mounted on said shaft and connected to the inner end of said bar, a spring carried by said arm and engaging a wall of the groove formed in said shaft and disposed to effect the clamping action of said 105 gripper member, a screw threaded in said arm and bearing against the outer end of said spring to vary the tension thereof, and a stop screw threaded in said arm and engaging a wall of the groove formed in said shaft and adapted to limit the thrust action of said spring.

7. A sheet gripping device comprising a gripper element, a rock shaft for operating said gripper element and provided with a groove therein, an arm loosely mounted on said shaft and engaging said gripper element, a compression spring carried by said arm and engaging a wall of the groove formed in said shaft and disposed to effect the clamping action of said 115 gripper element, and means carried by said arm for adjusting the tension of said spring.

8. A sheet gripping device comprising a gripper element, a rock shaft for operating said gripper element, an arm loosely mounted on said shaft, a compression spring carried by the hub of said arm and engaged with said shaft to form the medium for transfer of motion from said shaft to said 120 130

arm, a screw threaded into said hub and bearing against one end of said spring, and an abutment screw passing through said hub and acting to maintain said spring in compressed condition.

9. A sheet gripping device comprising a gripper element, a rock shaft for operating said gripper element, an arm loosely mounted on said shaft, a compression spring carried by the hub of said arm and engaged with said shaft to form the medium for transfer of motion from said shaft to said arm, a screw threaded into said hub and

bearing against one end of said spring, and an abutment screw passing through said hub and acting to maintain said spring in compressed condition, said shaft being formed with a groove against the opposite walls of which the said spring and abutment screw respectively bear.

Signed at New York in the county of New York and State of New York this 12th day of August A. D. 1924.

MARIA LOUISA WHITE,
*Executrix of the estate of Bruce Clark
White, deceased.*
